UNITED STATES PATENT OFFICE.

**LOUIE A. SHERMAN, OF ANOKA, AND HARRY E. SHERMAN, OF MINNEAPOLIS,
MINNESOTA.**

DESIGN FOR A SHOTGUN-SHELL.

51,974.

Specification for Design.

Patented Apr. 16, 1918.

Application filed November 6, 1917. Serial No. 200,629. Term of patent 14 years.

To all whom it may concern:

Be it known that we, LOUIE A. SHERMAN, a citizen of the United States, residing at Anoka, in the county of Anoka and State of Minnesota, and HARRY E. SHERMAN, a citizen of the United States, residing at Minneapolis, in the county of Hennepin and State of Minnesota, have invented a new, original, and ornamental Design for Shotgun-Shells, of which the following is a

specification, reference being had to the accompanying drawing, forming part thereof.

The figure is a plan view of a shot gun shell showing our new design.

We claim:

The ornamental design for a shotgun shell as shown.

**LOUIE A. SHERMAN.
HARRY E. SHERMAN.**
